UNITED STATES PATENT OFFICE.

HENRY N. HAGER AND JAMES E. FLYNN, OF THIEF RIVER FALLS, MINNESOTA.

PEAT AND LIGNITE BURNER.

Application filed July 17, 1923. Serial No. 652,105.

To all whom it may concern:

Be it known that we, HENRY N. HAGER and JAMES E. FLYNN, citizens of the United State, residing at Thief River Falls, in the county of Pennington and State of Minnesota, have invented a new and useful Peat and Lignite Burner, of which the following is a specification.

This invention relates to a stove which is especially adapted for burning peat, lignite, or other fuel of a similar nature.

In many parts of the country, which are located at a considerable distance from available coal deposits, and where by reason of the high cost of transportation and the excessive cost of the coal at the mines, the cost of such fuel is well nigh prohibitive, there are abundant deposits of lignite or the like, which may be obtained at a comparatively small cost, and which are available for fuel provided a suitable device may be obtained for utilizing the same.

With these facts in mind, it is the general object of the present invention to provide a device in which such fuel as lignite or peat may be successfully and economically burned.

A more specific object of the invention is to provide a device of this character in which practically all of the gases produced from the fuel by the heating of the same may be economically used for heating purposes, while the residue, which is in the nature of coke, charcoal or char may be also utilized for heating or may be produced as a by-product.

The nature of the invention and the specific structure of the preferred embodiment thereof will be more fully explained in connection with the accompanying drawing, in which—

Figure 1 is a vertical sectional view of a stove embodying our invention with the base of the stove shown in elevation.

Figure 2 is a sectional view of the same taken substantially on the line 2—2 of Figure 1.

Figure 3 is a sectional view taken substantially on the line 3—3 of Figure 1.

The stove comprises the usual cylindrical drum 5 having a fuel door 4, the lower end of the drum being tapered, as shown at 6, after the manner of the usual fire pot. This fire pot rests upon a suitable base

7, which provides a receptacle for the ashes

and has a front door 8 with the usual draft damper 9. The inner side of the base is provided with the usual flange 10, from which project shoulders or lugs 11 for supporting a grate 12.

At the upper end of the stove and suitably supported by the drum 5 is an annular rim 13, having a cover 14 which is pivoted at 15 to swing laterally, and is provided with a latch 16 cooperating with a keeper 17 to retain the cover in practically air tight relation to the rim 13. A fuel magazine 18 is suspended from the rim 13 and has a closed bottom 19 adapted to support a bucket 20, which contains the fuel. The bucket 20 is provided with a suitable bail 21, or similar means for lifting it out of the magazine to remove the coke, and to fill it with a fresh charge of fuel. Ribs 22 are preferably formed on the inner wall of the magazine 18 for guiding the bucket 20 and holding it in spaced relation to the wall of the magazine.

A gas pipe 23 extends through the wall of the magazine 18 and the drum 5 for conducting the gases produced by the heating of the fuel, and this pipe leads downwardly and through the wall of the ash pit or base 7, and terminates in a gas burner 24 located centrally of the grate 12. The grate is provided with suitable openings 25 for the ashes to drop into the base 7, and a plate 26 with corresponding perforations 27 is pivotally supported on the lower end of the gas pipe 23 and provided with a handle 28, by means of which it may be oscillated to shake the ashes into the pit 7.

In kindling a fire, the bucket 20 is filled with the lignite or peat, and a small wood fire is initially kindled within the fire pot 6. The heat from the wood fire starts the generation of the bituminous gases from the fuel in the bucket 20, and these gases are conducted through the pipe 23 to the gas burner 24. After the generation of the gas is once started, green fuel or coke may be used in the fire pot and the heat from the burning gas will assist in maintaining the fire so that the distillation of the peat or lignite in the magazine will continue until all the gas is expelled therefrom. The production of gas will be increased if the peat or lignite is saturated with water at the beginning of the opera-

tion, since the combination of the water with some of the excess carbon produces a certain proportion of water gas. When dry peat is used about twenty-five to thirty 5 per cent water should be added in order to get the best results. After the gas is generating freely, the stove should be closed up tight, whereupon a moderate fire may be maintained for half a day without re- 10 charging.

The drum 5 is provided at the top with the usual stove pipe 29 for the escape of the products of combustion. In order to prevent the pressure of gas within the magazine 18 from being excessive, it is advisable 15 to provide at the top an outlet pipe 30 having a branch 31 leading to the smoke pipe 29, and controlled by a spring-held safety valve 32. Whenever the pressure within 20 the magazine becomes high enough to be dangerous, the valve 32 will be pressed backwardly sufficiently to permit the escape of the excess gas through the branch 31 into the smoke pipe.

25 By means of this invention, the raw, wet peat, as it comes from the bog, or other wet or green fuel, may be placed directly within the magazine 18, and after the operation is once started the gas will be generated continuously until the fuel in the magazine is reduced to coke, charcoal or char. Lignite, slack, dust, screenings or other fuel may be treated in the same manner, but care should be taken that the fuel used should contain twenty-five to thirty 30 per cent of moisture. By means of this invention all such fuels containing a large percentage of bituminous gas may be economically burned with the highest degree of efficiency. The heat produced by the combustion of the gas is completely utilized by being burned at the base of the stove, so that the heat is radiated therefrom instead of passing out through the smoke flue.

40 It will, therefore, be seen that a greater number of heat units will be utilized, and with an ordinary stove all of the gases are burned at a point where the heat will be radiated into the room, and a continuous 45 and uniform operation is obtained without any difficulty being experienced from caking, and a consequent stoppage of the draft.

While we have shown and illustrated the specific details of one form in which the 50 invention may be embodied, it is to be understood that this is merely illustrative, and that various modifications may be made in the shape and proportions of the various parts, as well as in their relative arrangement without departing from the principles 55 of the invention or sacrificing any of the advantages thereof, and it is therefore our intention to include all such modifications 60 within the scope of the appended claims.

What is claimed is:

1. In a stove of the character described, 65 the combination of a drum provided with an air inlet opening and a smoke discharge pipe, a fuel magazine suspended from the top of the drum and having a closed bottom, a gas burner located within the drum beneath the magazine, a gas supply pipe leading from the magazine to said burner, a passageway leading from the magazine to the smoke pipe, and a safety valve 70 normally closing said passageway but responsive to a predetermined pressure to permit the escape of the gases into the smoke pipe.

2. In a stove of the character described, 75 the combination of a drum having a tapered base forming a fire pot, an air opening beneath the fire pot provided with a damper, a smoke discharge opening leading from the drum, a fuel magazine suspended within the 80 upper portion of the drum and having a closed bottom spaced from the bottom of the fire pot, a gas burner located at the bottom of the fire pot and having a gas supply pipe leading from the magazine, a 85 passageway leading from the magazine to the smoke discharge pipe, and a safety valve normally closing said passageway.

3. In a stove of the character described, 90 the combination of a drum provided with an air inlet opening and a smoke discharge pipe, said drum having an annular top, a fuel magazine suspended from said top and having a closed bottom spaced from the bottom of the drum, a substantially air tight 95 cover for said magazine, a gas burner located at the bottom of the drum, a gas supply pipe leading from the magazine to said burner, a passageway leading from the magazine to the smoke pipe, and a safety valve 100 normally closing said passageway but responsive to a predetermined pressure to permit the escape of the gases into the smoke pipe.

4. In a stove of the character described, 105 the combination of a drum having a tapered base forming a fire pot, a grate with a gas burner at its center, said grate and burner together forming the bottom of the fire pot, an air damper beneath the grate, a smoke 110 discharge opening in the upper portion of the drum, a normally closed fuel magazine disposed centrally of the upper portion of the drum and spaced from the bottom thereof leaving a clear space between the bottom 115 of the magazine and the bottom of the fire pot, and a gas pipe leading from the magazine to the gas burner.

5. In a stove of the character described, 120 the combination of a drum with its lower 125 end constituting a fire pot, a fuel magazine suspended within the drum and spaced from the bottom thereof to leave a clear space

for the fuel, an air tight cover for the magazine, said magazine containing a removable fuel receptacle resting on the bottom thereof but spaced from the sides of said magazine, said receptacle being removable through the top of the magazine when the cover is opened, a gas burner forming a part of the bottom of the fire pot, and a gas sup-

ply pipe leading from the magazine to the burner.

In testimony, that we claim the foregoing as our own, we have hereto affixed our signatures.

HENRY N. HAGER.
JAMES E. FLYNN.
